United States Patent Office

Des. 207,236
Patented Mar. 21, 1967

207,236

PITCHER

Marvin J. Fields, Baldwin, N.Y., assignor to Quality Importers, Inc.

Filed June 2, 1966, Ser. No. 2,522

Term of patent 14 years

(Cl. D44—21)

FIG. 1 is a side elevation of a pitcher showing my new design;

FIG. 2 is a plan view thereof looking downward;

FIG. 3 is a plan view thereof looking upward;

FIG. 4 is a front elevation thereof;

FIG. 5 is a rear elevation thereof;

FIG. 6 is a sectional view taken along lines 6—6 of FIG. 4.

I claim:

The ornamental design for a pitcher, as shown.
